US0D1015710S

(12) **United States Design Patent** (10) **Patent No.:** **US D1,015,710 S**
 (45) **Date of Patent:** **** Feb. 27, 2024**

(54) **SHOE INSERT**

- (71) Applicant: **OPVET Inc.**, Temple, TX (US)
 (72) Inventor: **Daniel E Norton**, Happy Valley, OR (US)
 (73) Assignee: **Opvet Inc.**, Temple, TX (US)
 (***) Term: **15 Years**
 (21) Appl. No.: **29/795,908**
 (22) Filed: **Jun. 21, 2021**

Related U.S. Application Data

- (63) Continuation-in-part of application No. 13/940,598, filed on Jul. 12, 2013, now Pat. No. 11,039,656.
